UNITED STATES PATENT OFFICE.

LEOPOLD KASSANDER, OF NEW YORK, N. Y., ASSIGNOR TO THE NATHAN MANUFACTURING COMPANY, OF NEW YORK, N. Y., A CORPORATION OF NEW YORK.

WATER-GAGE.

1,126,226.

Specification of Letters Patent.

Patented Jan. 26, 1915.

Application filed May 31, 1913. Serial No. 770,834.

To all whom it may concern:

Be it known that I, LEOPOLD KASSANDER, a citizen of the United States, residing at New York, in the county of New York and State of New York, have invented certain new and useful Improvements in Water-Gages, of which the following is a specification.

This invention relates to water gages adapted to be used in ascertaining the level of the water in steam boilers, and the like, and its novelty consists in the construction and adaptation of the parts as will be more fully hereinafter pointed out. In instruments of this class it is desirable that the sight glass should be thoroughly protected from injury and at the same time, danger of leakage should be avoided, and the described invention secures these desired ends efficiently and with economy.

In the drawings, Figure 1 is a front view of a device embodying the invention; Fig. 2 is a central vertical section thereof, and Fig. 3 is a transverse horizontal section on the plane of the line 3—3 in Fig. 1. Fig. 4 is a detail perspective view of certain of the compression members and a portion of the ring on which they are mounted.

In the drawings, 10 is the sight glass made of glass of usual form and dimensions, 11 is a casing made of suitable material as cast metal and provided with a vertical channel or recess 12 adapted to contain the column of water the height of which is to be ascertained.

13 and 14 are pipes or fittings secured to, or made integral with, the casing 11 and affording communication between the channel 12 and the water space of the boiler. The casing 11 is provided with two walls or side members 15, 15, the space between which is wider than the width of the sight glass 10 and terminating in a plane 16 slightly in front of the front surface of such glass. In front of the walls 15, there is arranged a cover plate 17 having a long central aperture 170 through which the front surface of the sight glass is viewed, and which cover plate is secured to the casing 11 by any suitable means as bolts and nuts indicated at 18. In the space between the sight glass 10 and

each wall of the casing there is arranged a suitable packing 19. Means are provided for keeping this packing in place without placing any undue strain upon the other parts of the device, comprising a series of straps 20 adapted to encircle the casing and provided with inturned flanges 21 which are adapted to contact with and press upon compression plates 22 which are inserted through apertures in the cover 17 provided for that purpose into the space between the sides of the sight glass and the walls of the casing and have their inner ends in the form of a continuous ring 22^a that bears against the packing 19. A set screw 23 is adapted to pass through each strap at the rear and to impinge against the rear wall of the casing. A suitable packing 24 is interposed between the sight glass and the casing, and a further suitable packing 25 is interposed between the sight glass and the cover 17.

What I claim is:

1. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last named packing consisting of a strap adapted to encircle the casing and provided with inturned flanges in combination with separable compression plates engaged by said flanges and arranged between the sight glass and the side wall and adapted to contact with such packing.

2. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last

- named packing consisting of a strap adapted to encircle the casing and provided with inturned flanges in combination with separable compression plates engaged by said flanges and arranged between the sight glass and the side wall and adapted to contact with such packing, and which plates are adapted to pass through suitable apertures in the retaining cover.
10. 3. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last named packing consisting of a strap adapted to encircle the casing and provided with inturned flanges in combination with separable compression plates engaged by said flanges and arranged between the sight glass and the side wall and adapted to contact with such packing, and means for securing the casing and cover together.
4. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last named packing consisting of compression plates arranged between the sight glass and each side wall of the casing, and means adapted to hold them in position.
5. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last named packing consisting of compression plates arranged between the sight glass and each side wall of the casing, and means adapted to hold them in position including a series of straps encircling the casing and contacting with the front edges of such plates.
6. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last named packing consisting of compression plates arranged between the sight glass and each side wall of the casing, and means adapted to hold them in position including a series of straps encircling the casing and contacting with the front edges of such plates.
7. A water gage comprising a casing provided with a water channel and side walls, a sight glass within the casing in front of said channel, an apertured retaining cover in front of the sight glass, a packing between the casing and the sight glass on each side of the channel, a packing between the cover and the sight glass on each side of the cover aperture, a packing between the sight glass and each side wall of the casing, and means adapted to compress the last named packing consisting of compression plates arranged between the sight glass and each side wall of the casing, and means adapted to hold them in position including a series of straps encircling the casing and contacting with the front edges of such plates, and each provided with means for securing it in position.
8. In a water gage, a casing having spaced side walls, a glass located between said side walls with its edges spaced therefrom, packing interposed between the side walls and edges of the glass, a retaining cover over said glass, and means separate from the cover and operating against the packing for compressing it in one direction and expanding it laterally against the casing walls and the edges of the glass, said means being movable with respect to the cover.
9. In a water gage, a casing having side walls, a glass located between said side walls, packing interposed between the side walls and glass, a retaining cover over said glass, and means passing through the cover and operating against the packing for compressing it in one direction and expanding it laterally against the casing walls and glass, said cover having openings through which the compressing means pass.
10. In a water gage, a casing having side walls, a glass located between said side walls, packing interposed between the side walls and glass, a retaining cover over said glass, and means separate from the cover and operating against the packing for compressing it in one direction and expanding it laterally against the casing walls and glass,

said means including a plurality of plates
passing through the cover, and devices bearing
against the outer ends of the plates for
forcing the same rearwardly, said cover
5 having openings through which the plates
pass.

In testimony whereof I affix my signature
in presence of two witnesses.

LEOPOLD KASSANDER.
